UNITED STATES PATENT OFFICE.

JOEL BARLOW FESLER, OF NEW YORK, N. Y., ASSIGNOR TO FESLER SALES COMPANY,
OF NEW YORK, N. Y., A CORPORATION OF DELAWARE.

FOUNTAIN-BRUSH.

1,190,228.

Specification of Letters Patent. Patented July 4, 1916.

Application filed July 9, 1915. Serial No. 38,909.

To all whom it may concern:

Be it known that I, JOEL B. FESLER, a citizen of the United States of America, and a resident of Richmond Hill, borough of 5 Queens, county of Queens, city and State of New York, have invented certain new and useful Improvements in Fountain-Brushes, of which the following is a specification.

My invention relates to improvements in 10 fountain brushes, that is to say, brushes comprising a reservoir for soap, mucilage, ink, paint or the like.

The particular brush herein illustrated and described is particularly intended for 15 use as a shaving brush, though suitable for other uses as well, and comprises improvements over the brushes illustrated and described in my patents Nos. 904,190, dated November 17, 1908, 1,006,641, dated October 24, 1911, and 1,067,596, dated July 15, 1913, and in my applications for Letters Patent Sr. Nos. 629,647, filed May 26, 1911, 70 762,847, filed April 22, 1913, and 855,744, filed August 8, 1914.

25 My invention comprises improved means for holding the bristle-tuft in place within the handle, an improved form for the lower end of the bristle-tuft-ferrule, or holder, whereby proper insertion of the feed tube 30 into the bristle tuft is insured when the bristle tuft is placed within the handle, means for preventing rotation of the reservoir within the handle, and other features, all as hereinafter described and particularly 35 pointed out in the appended claims.

The objects of my invention are to improve and simplify fountain brushes, and particularly to facilitate removal of the bristle tufts of such brushes from the handle, 40 and the connection of such bristle tufts to the handle, and to prevent rotation of the reservoir within the handle.

I will now proceed to describe my invention with reference to the accompanying 45 drawings, and will then point out the novel features in claims.

In said drawings: Figure 1 shows a central vertical section of a fountain shaving brush constructed in accordance with my 50 invention. Fig. 2 shows a perspective elevation of the lower portion of the bristle tuft and a fragmentary central vertical section of the coöperating upper portion of the handle of the brush, the said parts being 55 shown separated but positioned for connec-

tion one to the other. Fig. 3 shows a perspective elevation of the lower portion of the handle and of the end cap for that handle and the hand piece on such end cap, the end cap and handle being shown somewhat separated. Fig. 4 shows a horizontal section of the brush on the line $x-x$ of Fig. 1, looking downward; the reservoir being omitted. Fig. 5 shows a top view of the reservoir.

In the drawings, 1 designates the bristle tuft, 2 designates a ferrule constituting the bristle holder, 3 designates the main portion of the hollow handle, and 4 designates a ferrule fitting into and secured in the upper end of the handle 3 and adapted to receive the bristle holder 2, and to hold the same firmly, yet in such manner as to permit the bristle tuft with its bristle holder to be removed from the handle, when desired.

5 5 designates a central tube secured to, and in effect forming a part of, the bristle holder 2, through which tube the flexible feed tube 6 of the brush passes into the bristle tuft.

7 designates a removable reservoir within 80 the handle, and to which the feed tube 6 is connected, as hereinafter described; so as to be in effect a part of that reservoir.

8 designates an end cap for the handle, in this case arranged to be connected to the handle by means of bayonet-joint grooves 8^a adapted to engage bayonet-joint projections 3^a formed on the handle 3, such end cap 8 serving to hold the reservoir 7 in place; and 9 designates a hand piece rotatably mounted upon this end cap 8, and to which is connected the feed screw 10 extending up into the interior of the reservoir 7 and having mounted upon it a piston 11 adapted to force the plastic contents of 95 the reservoir into the feed tube 6.

The brush herein illustrated and described is particularly intended for use in 100 barber shops and the like, where attention is paid to sterilization of the brushes as well as other shaving equipment. In such cases, each barber is commonly provided with a number of bristle tufts 1, each having a ferrule or a bristle holder 2, which bristle tufts except when in use, are kept immersed in 105 a sterilization solution, or are otherwise kept in a sterile condition. In preparing to shave a customer the barber takes one of these bristle tufts from the sterilizing container and places the base or ferrule of such tuft in the 110

handle. It is desirable that such bristle tuft shall be capable of being connected to the handle quickly, also that the bristle tuft may be detached readily from the handle after the barber has finished using it on that particular customer. To this end I have provided the bristle-tuft-holder with a groove 41 near its base, adapted to be engaged by spring tongues 42 provided in a ferrule 4 secured in the top portion of the handle 3 and in effect forming a part of that handle. The ends of these spring tongues are provided with inwardly projecting portions, as shown particularly in Fig. 2, which are adapted to engage the groove 41 in the bristle holder 2. It will be seen that this form of catch is of such nature that the bristle holder 2, when inserted in the end of the handle 3, may be pushed down until the ends of the spring tongues 42 engage the groove 41, whereby the bristle tuft will be held firmly within the handle; nevertheless the bristle tuft, with its ferrule 2, may be pulled out from the handle readily, the spring tongues 42 yielding to permit this. Heretofore, the ferrules 2 of these bristle tufts have usually been arranged to screw into the end of the handle; a construction which is suitable, and indeed preferable, when the bristle tuft is to be removed rarely, if at all, from the handle, but when the bristle tuft is to be removed frequently from the handle, the construction above described, permitting the bristle tuft to be removed by a straight-line pull, and to be reinserted by merely pushing it into the handle, is much to be preferred.

In quickly placing a bristle tuft into a handle, as above described, there is a possibility that, if the base of the ferrule 2 be not properly constructed for the purpose, the feed tube 6, instead of entering properly into the bristle tuft, may be doubled over and folded down. To guard against this I have provided the bottom of the ferrule 2 with the dome-shaped bottom portion 44 which is adapted to guide the end of the feed tube 6 into the tube 5, when the base of the bristle tuft is inserted into the handle.

It is desirable that means shall be provided for preventing rotation of the reservoir 7 within the handle, when the hand piece 9 is turned to advance the piston 11. In former patents and patent applications I have illustrated the end cap 8 for the handle as screw-connected to the handle, and arranged to press the reservoir up within the handle against the bottom of the bristle tuft. But, I have found it extremely difficult to obtain reservoirs 7 of exactly uniform length. These reservoirs are commonly formed of glass, and it is well-known that it is difficult to get large numbers of glass tubes of the same length. Moreover, in a brush in which the bristle tuft is intended to be removed and replaced fre-

quently, a construction wherein the upper end of the reservoir is required to be forced tightly against the bottom of the bristle tuft or its holder, is objectionable, because it occasions difficulties in forcing the bristle tuft holder home. The reservoir 7 comprises a neck portion 25 having an outwardly turned flange 25^a, and the feed tube 6 (which usually is of rubber) has a broad base portion 24 adapted to fit over such flange 25^a; and to further hold the feed tube to the reservoir, a metal cap 26, centrally perforated for the passage of the feed tube 6, is applied above the base 24 of the feed tube and its edge is pressed or spun over the edge of the flange 25^a, so holding the feed tube firmly in place on the reservoir, and making it practically impossible to remove this feed tube from the reservoir, except by mutilation of the said metal cap 26. In the top of this metal cap I provide grooves 26^a, which are separated by undepressed portions 27 of the cap. I provide the handle 3 with a plate 45 having projections 45^a adapted to enter these grooves 26^a, when the reservoir is pressed into the handle, and thereby to lock the reservoir against rotation; for, if the reservoir be turned at all within the handle, these projections 45^a engage the projections 27 of the reservoir checking such rotation of the reservoir. The plate 45 acts as a stop to prevent the reservoir from moving upward when the hand piece 9 is rotated to thrust upward the piston 1.

What I claim is:

1. A fountain shaving brush comprising in combination a handle, a bristle tuft insertible into and removable from one end of said handle, a reservoir located within said handle and having a top cap structurally separate from the main portion of the reservoir but secured thereto, and provided with means adapted to be engaged to prevent rotation of said reservoir with respect to said handle, said reservoir also having a feed tube extending into said bristle tuft, a piston within said reservoir and screw means for advancing said piston, and means secured to said handle and projecting inward and engaging said reservoir cap and arranged to prevent rotation thereof during the actuation of said screw means.

2. A fountain shaving brush comprising in combination a handle, a bristle tuft insertible into and removable from one end of said handle, and having a base portion, and a ferrule within and forming a part of the handle and provided with a spring leaf formed from the body of such ferrule and projecting inward and arranged to engage such base portion and by such engagement to hold the bristle tuft removably within the handle.

3. A fountain shaving brush comprising in combination a handle, a reservoir located

within said handle and having a piston, and screw means for advancing said piston within said reservoir, said reservoir having a cap provided with projections, and said handle having means adapted to engage such projections and thereby to prevent rotation of the reservoir within the handle.

4. A fountain shaving brush comprising in combination a handle, a reservoir located within said handle and having a piston, and screw means for advancing said piston within said reservoir, said reservoir having a cap provided with circumferentially-incomplete grooves, said handle provided with means adapted to enter such grooves and by engagement with the ends thereof to prevent rotation of the reservoir within the handle.

5. A reservoir for fountain brushes and the like, comprising a container having at one end a discharge mouth, a feed tube having a base fitting over and engaging the outside of the mouth portion of the receptacle, and an end cap covering such base portion of the feed tube and centrally apertured for

the passage of the tubular portion of the feed tube and embracing the mouth portion of said receptacle, said end cap provided with means adapted to be engaged by retaining means for preventing rotation of the receptacle.

6. A fountain shaving brush comprising in combination a hollow handle, a reservoir located within said handle and having a piston, and means for advancing said piston within said reservoir, said handle having also bristle holding means and a partition between the reservoir and said bristle holding means, said partition forming a stop to prevent upward motion of the reservoir when the piston is actuated.

In testimony whereof I have signed this specification in the presence of two subscribing witnesses.
